UNITED STATES PATENT OFFICE

GEORGE W. BACH, OF ERIE, PENNSYLVANIA, ASSIGNOR TO UNION IRON WORKS, OF ERIE, PENNSYLVANIA, A CORPORATION OF PENNSYLVANIA

FURNACE

Application filed August 9, 1926. Serial No. 128,158.

It is desirable to provide the walls of boiler furnaces with a cooling medium and to accomplish this water tubes have been carried into the wall, or in such relation to the 5 wall as to cool the wall. In the present invention I have extended the cooling tubes for furnace walls directly from a boiler drum, thus simplifying the construction and increasing its efficiency. Features and details 10 of the invention will appear from the specification and claims.

The invention is illustrated in the accompanying drawings as follows:—

Fig. 1 shows a vertical section in a plane 15 from front to rear of the furnace.

Fig. 2 a section on the line 2—2 in Fig. 1. 1, 2 and 3 mark the three drums of an ordinary three-drum boiler, the connecting tubes being indicated in dash lines 4, 5 and 6, 20 it being understood that these merely represent the tube scheme and do not illustrate the full system. Tubes 7 lead from the front drum to a manifold 8.

The furnace has a front wall 9, a top wall 25 10, a rear wall 11 and side walls 12. Water tubes 13 extend from the front top drum downwardly to a manifold 14. Similar tubes 15 extend from the rear top drum 2 to the same manifold. The forward end of the 30 manifold 14 is connected with the manifold, or drum 8 by pipes 16 and with the drum 3 by pipes 17.

The tubes 13 and 15 are preferably arranged directly within the walls as clearly 35 shown in section in Fig. 2 but are at least in such relation to such walls as to cool and protect the same. It will be noted that the tubes 13 and 15 extend from the drums 1 and 2 in radial directions from the drum and fan out 40 from the drums to give the proper spread in the walls. Thus the fabricating is simplified and there is a direct connection and circulation between the cooling tubes and the boiler drums.

45 What I claim as new is:—

1. In a furnace, the combination of a drum; a boiler tube system connected lengthwise of and through the intermediate portions of the drum; a furnace wall through which 50 the drum extends; cooling tubes extending

radially and fan-wise from the drum, said cooling tubes being bent to distribute the tubes at intervals in parallel relation with their axes in a plane within the wall; and a manifold, arranged without the wall and connected to the ends of the tube opposite their connection with the drum, said manifold having its axis in a plane extending transversely of the axis of the drum. 55

2. In a furnace, the combination of a drum; a boiler tube system connected lengthwise of and through the intermediate portions of the drum; a furnace wall through which the drum extends; cooling tubes extending radially and fan-wise from the drum, said cooling 60 tubes being bent to distribute the tubes at intervals in parallel relation with their axes in a plane within the wall; and a manifold arranged without the wall and connected to the ends of the tube opposite their connection with the drum, said manifold having its axis in a plane extending transversely of the axis of the drum and the manifold being arranged 65 outside the furnace wall.

3. In a furnace, the combination of two upper drums; a boiler tube system extending lengthwise of and throughout the intermediate portions of said drums; a furnace wall to which the drums extend; cooling tubes extending radially and fan-wise from each of 70 said drums and arranged in a plane at right angles to the axes of the drums and adjacent to the ends of the drums, said tubes being bent to distribute the tubes at intervals in parallel relation to their axes in a plane in 75 cooling relation to the wall; and means connecting the ends of the tubes remote from the drums into the boiler system. 80

4. In a furnace, the combination of two upper drums; a boiler tube system extending lengthwise and throughout the intermediate 90 portions of said drums; a furnace wall to which the drums extend; cooling tubes extending radially and fan-wise from each of said drums and arranged in a plane at right angles to the axes of the drums and adjacent to the ends of the drums, said tubes being bent to distribute the tubes at intervals in parallel 95 relation to their axes in a plane in cooling relation to the wall; and means connecting 100

the ends of the tubes remote from the drums into the boiler system comprising a manifold having its axis in a plane extending transversely of the axes of the drums.

5 In testimony whereof I have hereunto set my hand.

GEO. W. BACH.
